UNITED STATES PATENT OFFICE

100,276

DESIGN FOR A PARKING METER

Howard Masterson, Burbank, Calif.

Application May 1, 1936, Serial No. 62,396

Term of patent 14 years

To all whom it may concern:

Be it known that I, Howard Masterson, a citizen of the United States and a resident of Burbank, in the county of Los Angeles and State of California, have invented a new, original, and ornamental Design for a Parking Meter, of which the following is a specification, reference being had to the accompanying drawing, forming a part thereof.

The figure is a perspective view of a parking meter showing my new design.

The numerals appearing on the upper portion of the design are merely representative.

I claim:

The ornamental design for a parking meter, as shown and described.

HOWARD MASTERSON.
